UNITED STATES PATENT OFFICE.

BERNARD E. McLAUGHLIN, OF MELROSE PARK, ILLINOIS.

ADJUSTABLE STRAIGHTEDGE.

Application filed December 28, 1926. Serial No. 157,505.

This invention relates to improvements in the construction of a straight edge, particularly adapted for use by paper hangers.

In practicing the art of paper hanging, it is essential for good workmanship that the straight edges used to trim the paper, shall have as nearly a perfectly straight edge from end to end, as possible for obtaining a true edge on paper trimmed, for purposes well known in the art.

It is an object of this invention to provide a straight edge for paper hangers' use which is adjustable in order that it may be set true by the paper hanger at frequent intervals, wherever the edge is set up for trimming paper.

This is necessary in view of the wood or metal, or a combination of both, which are used in making up straight edges for paper hangers are known to get out of true due to weather conditions or the particular manner in which the edge is set up for a special cutting job. The provision of the adjustable straight edge of this invention overcomes this difficulty.

A further object of the invention resides in providing a straight edge and construction for paper hangers' use which is of the most simple structure, in order to produce a straight edge which may be made at a substantially low cost, and which at the same time, may be readily adjusted with the use of tools already used by paper hangers in their work, so that the edge may be readily trued in a minimum of time.

The invention comprehends numerous other objects residing in the details of construction, and the arrangement of the parts, which are more particularly pointed out in the following detailed description and claims directed to a preferred form of the invention, it being understood, however, that various changes in the size, shape, and arrangement of the parts may be made without departing from the spirit and scope of the invention as herein set forth.

In the drawing forming a part of this application:—

Figure 1 is a plan view of the improved straight edge forming the subject matter of this invention.

Fig. 2 is a side elevation thereof.

Fig. 3 is a vertical sectional view taken on the line 3—3 of Fig. 2.

Fig. 4 is a diagrammatic view used for il-

lustrating how the straight edge is adjusted in accordance with this invention.

The straight edge includes a body member 1 made up of a plurality of elongated interlocked pieces to provide a rigid construction of the body member which has the brass strip 2 secured to one edge thereof in order to protect the wood body member 1 from having its edge portion damaged in being handled.

A flexible strip member is indicated at 3, which is co-extensive with the body member 1 and is positioned at the opposite side edge thereof as clearly shown in Fig. 1. This strip member 3 has a rabbeted groove formed in one face thereof as indicated at 4, opening through the side edge toward the body member.

A U-shaped bar member 5 of suitable metal preferably brass, is mounted over the opposite side edge and the outer edge of the strip member 3 which is shown in Fig. 3, and suitably secured to the strip by screws 6 at predetermined spaced intervals, threaded into the material thereof.

Intermediate the screws 6 and at predetermined spaced intervals the U-shaped member 5 over the edge portion, the strip 3 is formed with a plurality of openings 7, and the strip 3 immediately adjacent and in the rear of these openings is formed with a plurality of small bores 8 terminating in the rear of the strip in enlarged sockets 9. Adjusting screws 10 have the shank portions extending through the bores 8 which are in axial alignment with the openings 7 and the heads 11 positioned in the enlarged sockets 9, while the end portions of the shanks as indicated at 12, are threaded in any desirable manner for threaded engagement in the body member 1 of the straight edge.

This structure is shown particularly in Fig. 3, and it will be noted that the mounting of the adjusting screw 10 is such that the fit in the strip 3 is substantially tight and without any play or looseness, but it is to be understood that the screws 10 are freely rotatable in this assembled position in order to adjust strip 3.

Suitable screw members 13 are mounted in the opposite ends of the strip 3 and have lateral extensions formed with eyes 14 in which is secured the thread or cord member 15.

In the use of the straight edge forming this

invention, the paper hanger upon setting up the body member 1 of the edge on the job, will first adjust the opposite end of the strip member, by operating the set screws 10 nearest the ends of the edge so as to set the ends of the strips 3 to the proper gauge for the work to be done. This setting of the ends of the strip member is illustrated clearly and diagrammatically in Fig. 4 at 16, following which the cord member 15, is set so as to lie within the plane of the edge portion of the U-shaped member 5 applied to the strip member, as clearly shown in Fig. 4. Then the paper hanger, with the use of a screw driver, sets each of the screws 10 by turning the same in or out, so as to adjust the strip member 3 in order that the face of the U-shaped member 5 will lie in the same plane as the cord 15.

20 As a result, the cord 15 which is stretched tight or taut, and the careful setting of the strip member 3 will provide the proper straight edge for the work. Should the straight edge get out of adjustment, it may be readily reset in the same manner.

25 It will thus be seen that a highly simple form of straight edge construction has been provided in which a screw member 10 and the U-shaped member 5 cooperate with the strip 3 to provide an adjustable straight edge structure which is highly simple in construction, efficient in operation, and of a character that it may be readily adjusted by the ordinary screw driver inserted through the opening 7 in the U-shaped member 5.

30 Having thus described my invention, what I claim as new is:—

35 1. An adjustable straight edge comprising a body member, a flexible strip member, 40 screw members rotatably journaled in the

flexible strip member having engagement in the body member for axial movement therein upon rotation to adjust the strip member relative thereto, and a retaining member mounted on the edge of the strip member 45 for retaining said strip member and the adjusting screw members in assembled relation.

2. An adjustable straight edge comprising a body member, a strip member extending throughout the length of the body member at one side portion thereof, adjusting screws rotatably mounted in the strip member and threadedly mounted in the body member, and a retaining member applied to the strip member for retaining the screw members and strip member in assembled relation.

3. An adjustable straight edge comprising a base member, an adjustable strip member at one side of the base member, a U-shaped member mounted over the edge of the adjustable strip member and rigidly secured thereto, and adjusting screws threadedly mounted in the strip member and retained in assembled relation by said U-shaped member, having threaded engagement with the body member and adapted, upon rotation, to vary the position of the strip member adjacent the body member.

4. An adjustable straight edge comprising a body member, a flexible strip member, means for adjustably attaching said flexible strip member to the body member, and means carried by the flexible strip member adapted for cooperation therewith to indicate any deviation from a straight line along the edge of said strip member.

In testimony whereof I affix my signature.
BERNARD E. McLAUGHLIN.
